REVOKING SHUTTLE FEELER CARRIED
WEFT CUTTER

Rudolf Hrdina, Hradec Kralove, Czechoslovakia

Application September 2, 1948, Serial No. 47,413
In Czechoslovakia December 5, 1947

6 Claims. (Cl. 139—267)

1

The present invention relates to the automatic changing of bobbins in looms, and particularly to a shuttle feeler mechanism and weft thread cutting device. The present invention constitutes an improvement over the operation and construction of the weft stop motion device disclosed in my United States Patent 2,027,776.

Various devices have been developed in the past for determining the bobbin changing position of a shuttle, for cutting the weft thread when a break in the thread occurs and for pulling the broken weft thread out of the range of the warp threads. The shuttle position determining device is referred to as a feeler and comprises a rod adapted to enter an aperture in the shuttle, the feeler and aperture being so positioned relatively that the feeler enters the aperture only when the shuttle is in the proper position for a bobbin changing operation. In certain of the prior art devices the mechanism for cutting the thread has been arranged integrally with the shuttle feeler mechanism and the two normally penetrate the shuttle box and the shuttle wall through a common aperture for convenience sake and to avoid unnecessary weakening of the shuttle box and shuttle wall.

In the prior devices, the feeler and cutter were normally hinged to the bobbin feeding mechanism and particularly to the bobbin change hammer so as to swing from a position in which the feeler was directed obliquely downwardly below the shuttle to a position wherein the shuttle feeler was in substantially horizontal alignment with the apertures in the shuttle box and shuttle wall. After the cutting operation and the bobbin changing operation had been completed, the device was again swung downwardly to a position below the shuttle. Separate mechanism associated with the thread stop motion was required to effect the raising and lowering movement. It has been found in practice that the raising and lowering of the feeler and cutting mechanism causes a vibration thereof, thus rendering the mechanism incapable of proper alignment with the apertures. Constant care and checking of the device have been required to maintain it operative and to insure against a breakdown of the loom.

It is, therefore, a primary object of the present invention to eliminate the swinging movement of the feeler and cutting mechanism and to provide a simple reciprocatory movement for the mechanisms. Such movement can be accomplished with less actuating mechanism than that required by previous devices and will, of course,

aid in the prevention of vibration of the feeler and cutter.

Another object of the invention is to provide a support for the feeler and cutter throughout its movement to guide the device in its movement and to assist in the prevention of vibration.

Other objects and features of the invention will be disclosed in the following description wherein reference is made to the accompanying drawings, in which:

Figure 1 is a side elevation of the weft stop motion device as associated with a shuttle and shuttle box;

Figure 2 a plan view of the device illustrated in Figure 1;

Figure 3 a side elevation of the device as associated with its actuating mechanism and a bobbin hammer;

Figure 4 an end view of the mechanism illustrated in Figure 3;

Figure 5 a view partly in cross-section taken on the line 5—5 of Figure 3; and

Figure 6 a view partly in cross-section taken on the line 6—6 of Figure 4.

Referring particularly to Figures 1 and 2, a shuttle 1 having an aperture 2 therein and carrying a weft bobbin 3 is associated with a shuttle box 5 which is provided with an aperture 6 with which the aperture 2 will align when the shuttle is in proper position for a bobbin changing operation. The shuttle box 5 is carried by a slay, not illustrated. An abutment 7 is provided on the slay for a purpose to be described hereinafter.

The weft stop motion device consists of a hollow rod 8 within which is mounted for reciprocation a piston 12. A slot is provided in the side wall of the rod 8 and a screw or a pin is affixed to the piston 12 through the slot to limit the movement of the piston 12 in the rod 8. A spring 11 is positioned within the rod 8 and constantly urges the piston 12 to its most extended position.

A two arm lever 16, 17 is pivotally secured to the rod 8 by means of the pivot pin 15. One end of the arm 17 is bent laterally outward to form a pin 18. A pawl 19 positioned to engage the abutment 7 on the slay is pivotally secured to a shoulder formed on the piston 12.

A U-shaped feeler is secured to the forward end of the piston 12 and is adapted to be inserted into the apertures 2 and 6. The front end of the feeler 20 is provided with a slot 21 for the reception of the weft thread. Between the legs of the U-shaped feeler a cutting blade 22 is stationarily mounted and a movable blade 23 and thread gripping device 24 are movably mounted for a re-

stricted oscillatory movement. A rock shaft 25 extends through the legs of the feeler and is operatively associated with the movable blade 23 and the thread gripping device 24. A lever 26 extending parallel to the piston 12 is formed integrally with the rock shaft 25 and is adapted to oscillate the rock shaft.

In operation, as the device is moved inwardly through the apertures 2 and 6, the pawl 19 engages the abutment 7 and is moved angularly about its pivot to a limit defined by the coacting relationship of the face of the abutment 7 and the face of the pawl 19, wherein its opposite end is in a position to engage the arm 16 of the two arm lever. On continued movement the rod 8 will slide over the piston 12 bringing the arm 16 into contact with the pawl 19. The lever 16, 17 will be pivoted about the pin 15 until the pawl 19 engages a recess 14 formed in the rod 8. This positively prohibits further movement of piston 12 relative to the rod 8. As illustrated in Figure 2, the pin 18 contacts the lever 26 so that when the arm 16 is moved rearwardly and upwardly the arm 17 will be moved to deflect the lever 26. As the feeler 20 was passed through the apertures 2 and 6, the weft thread 4 was picked up in the slots 21. When the lever 26 is actuated by the arm 17 and the pin 18, the rock shaft 25 is oscillated and the thread grip 24 is moved to hold the thread 4. During the same movement, the moveable blade 23 is moved with respect to the stationary blade 22 and the thread 4 is cut.

According to the operation of the loom a bobbin change is effected at this time and the weft stop motion device is retracted pulling the weft thread 4 with it and removing the thread from the range of the warp threads.

The operation of the weft stop motion device is effected by means of the mechanism illustrated in Figure 3. When a break in the weft thread occurs the thread guard and stop motion of the loom effect a partial rotation of a shaft 29 in the direction of the arrow A causing the gear segment 30 associated therewith to effect a partial rotation of the gear 31. A link 33 affixed to the pin which is secured to the piston 12 through the slot in the wall of the rod 8 is operatively connected to the gear 31 through a link 32. (Figures 3 to 6). As the gear 31 is given a partial rotation the links 32 and 33 allow the piston 12 to move forwardly, and at the same time to move the bobbin hammer 10 by moving rod 8 and the clamp 28 which pivotally connects the rod 8 and the hammer 10. At this time the slay is moving in the opposite direction by virtue of the customary loom controls. When the movement of the piston 12 is stopped by virtue of the pawl 19 engaging the abutment 7, the rod 8, relatively speaking, will be slid forwardly along the piston 12 until the pawl 19 engages in the recess 14. During the movement of the rod 8, the two arm lever 16, 17 is actuated thus effecting the cutting of the weft thread. When the rod 8 is stopped by the pawl 19 the hammer 10 will pivot about the connection between it and the clamp 28 to insert a new bobbin into the shuttle. After this operation has been completed the slay will be returned to its normal position and the feeler will remain temporarily in its extended position and will withdraw the thread as required in a substantially reverse order. The return of the mechanism is caused by well-known loom mechanism and controls in conjunction with the already described apparatus.

Should the shuttle be out of position so that

the aperture 2 therein does not align with the aperture 6 in the shuttle box 5, the feeler will abut against the wall of the shuttle and will be telescoped into the rod 8 before the pawl 19 engages the abutment 7. Due to the fact that there is no movement of the pawl 19 it will not engage in the recess 14 on the rod 8 and the rod will slide forwardly until the return movement is started. Due to the fact that the movement of the rod 8 is not stopped, the hammer 10 will not be actuated to insert a new bobbin in the shuttle.

It is clear, therefore, that the feeler mechanism prevents the actuation of the hammer 10 when the shuttle is not in the proper position for a bobbin change.

The feeler mechanism has a linear movement only. This movement is insured by reason of the support 34 acting on the projection 13 of the rod 8. The support serves to unerringly guide the feeler into the aperture 6 and to prevent vibration. As the slay reaches its normal position the thread guard will be returned to its normal position, thus causing the rod 8 and other parts of the device to be returned to their normal positions.

The shuttle feeler mechanism will remain in its normal position until again actuated on the next breaking of the weft thread.

It is clear that the above described structure is but one embodiment of my invention and that various mechanical designs can be utilized to accomplish the same result. I, therefore, desire to define my invention, not by the preceding description but, by the following claims.

35 I claim:

1. In a shuttle feeler mechanism for looms, the combination with a slay, a bobbin hammer, a shuttle box and a shuttle, of a two piece telescope feeler rod mounted on said hammer for reciprocation in a horizontal plane toward and from said shuttle, means for reciprocating said rod, said shuttle box and said shuttle having apertures therein, the aperture in said shuttle being aligned with the aperture in said shuttle box when said shuttle is in position for a bobbin changing operation, said rod being aligned with the aperture in said shuttle box for reciprocation into and out of said apertures, a pawl pivotally secured to said rod, an abutment on said slay positioned to be engaged by said pawl, a thread cutting device mounted on said rod and arranged to enter said apertures, means operatively associating said pawl with said thread cutting device, said pawl being positioned on said rod to engage said abutment only when said rod enters both said apertures, said cutting device being actuated by said pawl through said associating means when said pawl engages said abutment, and means forming a part of said rod adapted to coact with said pawl only when said pawl engages said abutment to effect actuation of said hammer.

2. In a shuttle feeler mechanism for looms, the combination with a slay, a bobbin hammer, a shuttle box and a shuttle, of a two piece telescopic feeler rod mounted on said hammer for reciprocation in a horizontal plane toward and from said shuttle, means for reciprocating said rod, said shuttle box and said shuttle having apertures therein, the aperture in said shuttle being aligned with the aperture in said shuttle box when said shuttle is in position for a bobbin changing operation, said rod being aligned with the aperture in said shuttle box for reciprocation into and out of said apertures, a pawl pivotally secured to said rod, an abutment on said slay

positioned to be engaged by said pawl, a thread cutting device mounted on said rod and arranged to enter said apertures, means operatively associating said pawl with said thread cutting device, said pawl being positioned on said rod to engage said abutment only when said rod enters both said apertures, said cutting device being actuated by said pawl through said associating means when said pawl engages said abutment, means forming a part of said rod adapted to coact with said pawl only when said pawl engages said abutment to effect actuation of said hammer, and a stationary support for said feeler rod for supporting and guiding said feeler rod during reciprocation thereof in a horizontal plane.

3. In a shuttle feeler mechanism for looms, the combination with a slay, a bobbin hammer, a shuttle box and a shuttle, of a two piece telescopic feeler rod mounted on said hammer for reciprocation in a horizontal plane toward and from said shuttle, means for reciprocating said rod, said shuttle box and said shuttle having apertures therein, the aperture in said shuttle being aligned with the aperture in said shuttle box when said shuttle is in position for a bobbin changing operation, said rod being aligned with the aperture in said shuttle box for reciprocation into and out of said apertures, a pawl pivotally secured to said rod, an abutment on said slay positioned to be engaged by said pawl, a rock shaft mounted on said rod transversely thereof, a thread cutting device mounted on said rock shaft and arranged to enter said apertures, a lever pivotally secured to said rod and arranged to coact with said pawl and said rock shaft, said pawl being positioned on said rod to engage said abutment only when said rod enters both said apertures, said pawl upon engagement with said abutment pivoting to engage and cause pivotal movement of said lever which transmits an oscillatory movement to said rock shaft to actuate said thread cutting device, means forming a part of said rod adapted to coact with said pawl only when said pawl engages said abutment to effect actuation of said hammer, and a stationary support for said feeler rod for supporting and guiding said feeler rod during reciprocation thereof in a horizontal plane.

4. In a shuttle feeler mechanism for looms, the combination with a slay, a bobbin hammer, a shuttle box and a shuttle, of a two piece telescopic feeler rod mounted on said hammer for reciprocation in a horizontal plane toward and from said shuttle, means for reciprocating said rod, said shuttle box and said shuttle having apertures therein, the aperture in said shuttle being aligned

with the aperture in said shuttle box when said shuttle is in position for a bobbin changing operation, said rod being aligned with the aperture in said shuttle box for reciprocation into and out of said apertures, a shaft actuated by said loom upon the breaking of the weft thread, a gear segment secured to said shaft, a gear arranged to mesh with said gear segment, a first link associated with said gear for rotation thereby, and a second link pivotally connected to said first link at one end and to said rod at the other end to effect reciprocation of said rod in a horizontal plane upon actuation of said shaft.

5. A shuttle feeler and weft thread cutting mechanism for looms, comprising, a two piece telescopic feeler rod, a pawl pivotally secured to one piece of said rod, a lever pivotally secured to the other piece of said rod, a feeler affixed to one end of said rod, cutting blades mounted on said feeler, and a rock shaft mounted on said feeler and associated with one of said blades to oscillate said blade, said shaft extending adjacent said lever and being operatively associated therewith, said pawl being actuatable to move said lever to rock said shaft to oscillate said blade associated with said shaft relatively to another blade.

6. A safety device for weft stop motion of looms having a slay, a bobbin hammer, a shuttle and a shuttle box, comprising, a two piece telescopic feeler rod, means arranged to move said feeler rod into and out of engagement with said shuttle, means associated with said feeler rod for controlling actuation of said hammer, and a support for said feeler rod, said first mentioned means including a linkage associated with the thread stop motion of the loom, said rod being reciprocated in a single plane and on a horizontal axis substantially parallel to said slay by said linkage, said support acting to guide said rod in its reciprocation in said single plane.
